UNITED STATES PATENT OFFICE

ALPHONSE F. MONEUSE, OF NEW YORK, N. Y.

MIXING FAUCET.

Application filed November 29, 1922. Serial No. 603,960.

To all whom it may concern:

Be it known that ALPHONSE F. MONEUSE, citizen of the United States, residing at New York, in the county of New York and State of New York, has invented certain new and useful Improvements in Mixing Faucets, of which the following is a specification.

This invention relates to faucets, and has 10 special reference to mixing faucets.

More particularly, the invention relates to mixing faucets peculiarly adapted for use in connection with coffee, milk, and other like urns such as are used in hotels, restaurants 15 and lunch rooms.

One important object of the invention is to improve the general construction of a device of this character.

A second important object of the invention is to provide and improve a mixing faucet adapted to be used for liquids wherein special means exist whereby the faucet may be readily cleaned out.

A third important object of the invention is to provide an improved faucet of this description wherein means exist, independent of the mixing valve, for cutting off the flow through one of the channels of the faucet.

A fourth important object of the invention is to provide an improved arrangement of urn and piping in connection with such a faucet.

With the above and other objects in view as will be hereinafter apparent, the invention consists in general of certain novel details of construction and combination of parts hereinafter fully described, illustrated in the accompanying drawings and specifically claimed.

In the accompanying drawings, like characters of reference indicate like parts in the several views, and:—

Fig. 1 is a front elevation of the faucet.

Fig. 2 is a side elevation thereof.

Fig. 3 is a longitudinal section therethrough.

Fig. 4 is a diagrammatic view of the urn and piping arrangement.

In carrying out the objects of this invention, there is provided a valve body 10, having a lower passage 11, which extends through a rearwardly projecting pipe connection 12, threaded as at 13 for screwing

55 into an urn or union. Above the passage 11 is a second passage 14, which extends

through a rearwardly projecting tubular member 15, threaded internally at its rear end as at 16, so that a nipple may be screwed therein. These passages 14 and 11 60 are entirely separate from each other except at the forward end of the body where they curve downward and unite in a common outlet 17. Moreover, the passages 14 and 11 have at their forward ends suitable 65 threaded openings for the reception of clean-out plugs 18, which are alined with said faucets. Intermediate the ends of the horizontal portions of the passages is formed a valve chamber 19, wherein is fitted a tapered plug valve 20, having an upper fluid passage 21, and a lower fluid passage 22, which may be brought into registry with the respective passages 14 and 11 by means of a handle 23, fitted at the upper end of 70 the plug valve. This plug valve is provided with the usual spring washer 24, and retaining screw 25 at its lower end. Between the valve 20, and the rear end of the passage 11 is formed a second valve seat 75 80 wherein is provided a plug valve 26, fitted with a thumb piece 27 for rotating the same, this valve being provided with a passage 28, which may be brought into registry with the passage 11. This valve is likewise provided 85 with a spring washer 29, and retaining screw 30.

By reason of the extension of the portion 12 rearwardly of the passage 14, ready connection is afforded to the piping from 90 the urns. Furthermore, the provision of the valve 26 permits cutting off of the flow of fluid through the passage 11, while leaving the passage 14 to be opened and closed by the valve 20. In Figure 4, the double 95 faucet is indicated in general at F, and the upper passage 14 is connected by a T 31 to branch pipes 32, each provided with a cut-off valve 33, and connected respectively to milk and chocolate urns as shown. The 100 lower passage is connected directly to the coffee urn, the valve 27 serving to cut-off this urn when desired. Thus the arrangement is such that milk alone, coffee and milk, chocolate alone, or chocolate and milk, 105 may be all served by proper manipulation of the valves.

There has thus been provided a simple and efficient device of the kind described, and for the purpose specified.

It is obvious that minor changes may be made in the form and construction of

the invention without departing from the spirit thereof. It is not, therefore, desired to confine the invention to the exact form herein shown and described, but it is desired to include all such as properly come within the scope claimed.

Having thus described the invention, what is claimed as new, is:

1. In a faucet of the class described, a valve body having upper and lower tubular portions provided with passages extending longitudinally therethrough, said portions being arranged to provide a plug valve seat intermediate their ends, the passages through said portions being curved downwardly and uniting in a common outlet at the front of the body, the upper tubular portion uniting with the lower tubular portion in front of the valve seat, a plug valve fitted in the valve seat and having ports extending diametrically through in parallel relations and movable into and out of registry with the respective passages.
2. In a faucet of the class described, a valve body having upper and lower tubular portions provided with passages extending longitudinally therethrough, said portions being arranged to provide a plug valve seat intermediate their ends, the passages through said portions being curved downwardly and uniting in a common outlet at the front of the body, the upper tubular

portion uniting with the lower tubular portion in front of the valve seat, a plug valve fitted in the valve seat and having ports extending diametrically through in parallel relations and movable into and out of registry with the respective passages, and a shut-off valve between the rear end of the lower passage and the plug valve.

3. In a faucet of the class described, a valve body having upper and lower tubular portions provided with passages extending longitudinally therethrough, each portion being provided with a valve seat, a plug valve in said seats and having openings therethrough adapted to be brought into and out of registry with the passages, the said upper and lower portions being curved downwardly at their forward ends and uniting in a common outlet, both of said outlets being in front of the plug valve, and a pair of clean-out plugs each aligned with the horizontal portions of a respective passage whereby said plugs are adapted to permit the cleaning of the horizontal portions of both passages throughout their entire lengths.

In testimony whereof I affix my signature in presence of two witnesses.

ALPHONSE F. MONEUSE.
